F. J. KIENEL

HOSIERY DRYING FORM

Filed Oct. 8, 1925

UNITED STATES PATENT OFFICE.

FREDERICK J. KIENEL, OF PHILADELPHIA, PENNSYLVANIA.

HOSIERY-DRYING FORM.

Application filed October 8, 1925. Serial No. 61,267.

My invention relates to an improvement in hosiery drying forms and more particularly in drying forms of the type adapted to be internally heated.

Heretofore it has been customary to dry hosiery by placing it upon a hollow form the external surface of which has the desired shape of the hosiery to be dried. The form is internally heated by steam or electricity and hosiery placed thereon in a damp condition is dried and set to shape.

The drying forms heretofore used, while satisfactory for ordinary forms of hosiery, which are essentially shaped in the knitting operation, have no capacity for materially shaping or folding the hosiery. For example, in the manufacture of half hose, it is known to produce the leg and welt or top portion in one operation by continuous knitting, thus avoiding the necessity for transferring a knitted top from a top knitting machine to a leg and foot knitting machine. Half hose made in this manner are, however, open to the objection that the top or welt is of the same size as the upper part of the leg, which, while in fact an advantage in manufacture and in use, is, from a marketing standpoint, a disadvantage, since such hose appear different from the ordinary in the size of the top or welt and do not pack neatly.

Hose of the character formed by continuous knitting of the leg and top or welt may be made to have an attractive appearance and to pack neatly by so folding the top or welt portion as to make it conform in dimensions with the separately knitted welt or top, as for example, as disclosed in an application for patent filed by me July 24, 1925, Serial Number 45,739, but heretofore there has been no form obtainable for drying the stocking and at the same time folding and pressing the top or welt in the manner indicated, and it is the object of my present invention to produce such a form.

Further, my invention has for an object the provision of means adapted to hold the hose on the form.

Having now indicated, in a general way, the nature and purpose of my invention, I will proceed to a detailed description thereof, with reference to the accompanying drawings, in which is illustrated a preferred embodiment, and in which—

Fig. 1 is a side elevation partially in sec-

tion of a drying form embodying my invention.

Fig. 2 is a cross-sectional view on line 2—2, Fig. 1.

a indicates a section of pipe upon which the form *b* is mounted, the pipe *a* being supported in a table in any usual manner.

The interior of the form is divided into sections by a partition *c*, which extends nearly to the toe of the form. One section of the form is connected to a live steam pipe *d* extending through pipe *a*, while the other is in communication with pipe *a*, which, in addition to supporting the form, serves as a discharge conduit for steam from the form.

The form adjacent the end of that portion adapted to be embraced by the leg portion of a stocking is reduced in size and grooves *e* of substantial depth are formed in the edges of the reduced portion.

A collar *f* is clamped on the form adjacent its base and serves to support a pair of levers *g* through the medium of a pivot *h*. At the upper end of each of the levers is pivotally mounted a blade *i* adapted to be entered in the slots *e* in opposite edges of the form, the levers *g* being offset so as to bring the blades in the plane of the slots.

Links *j* are pivotally attached to the lower ends of the levers *g* and by means of a single pivot to the upper end of a rod *k*, the lower end of which is connected to a foot treadle *l* suitably mounted on the floor. A spring *m* is attached to a bracket *n* on the floor and to a collar *o* on the rod *k*.

The connection between rod *k* and foot treadle *l* is made between a pair of nuts *p* threaded on the end of rod *k* and by the adjustment of which the effective length of rod *k* may be varied. The collar *o* may be adjusted on rod *k*, thus permitting variation in the tension of the spring *m*.

The operation of the device will be readily understood if it is noted that levers *g* will be moved around their pivot *h* through vertical movement of the rod *k* connected to the levers through links *j* and on movement of levers *g* about their pivot blades *i* will be entered into and withdrawn from the grooves *e* in the edges of the form. Vertical movement of rod *k* is accomplished upwardly by depression of the treadle *l* against the action of spring *m*, which serves to move the rod *k* downwardly on release of the treadle. The blades *i* are entered into the grooves *e*

by downward movement of rod *k* under the influence of spring *m* and are withdrawn by depressions of the treadle *l* by an operator.

In the treatment of hosiery on the form above described, the treadle is depressed, withdrawing the blades from the grooves and the stocking drawn over the form. When fully on the form, the top of the stocking will overlie that portion of the 5 form in which are formed the grooves *e*. The treadle is then released and the action of spring *m* causes the blades *i* to enter the grooves carrying within them the slack of the top of the stocking and folding it in. 10 The tension of spring *m* holds the blades in place in the grooves until the folds in the top are set and the stocking dried, after which the blades are withdrawn by depression of treadle *m* and the stocking removed 15 from the form.

The blades also act to clamp the hose to the form and prevent creeping of the hose during the drying thereof.

The finished stocking will have the edges 20 of its top infolded and shaped in the most convenient manner for appearance and neatness in packing.

It will be understood that the apparatus described may be modified in various ways 25 and that a series of forms may be connected to be actuated by a single treadle, without departing from my invention.

Having now fully described my invention, what I claim and desire to protect by 30 Letters Patent is:

1. Means for drying and shaping hosiery comprising, in combination, a hollow internally heated drying form having foot and leg shaping portions, the leg shaping portion having a cuff folding portion with 35 grooves formed in its edges, and blades adapted to force a portion of a stocking on said form into said grooves.

2. Means for drying and shaping hosiery 40 comprising, in combination, a drying form having a foot, leg, and top-receiving portions, grooves formed in the edges of the top-receiving portion of the form, and blades adapted to be entered into said grooves to 45 force a portion of the top of a stocking

therein and hold the stocking during the drying thereof.

3. Means for drying and shaping hosiery comprising, in combination, a drying form having a groove formed in one of its edges, 55 a blade pivotally mounted adjacent the form and adapted to be moved into and out of said groove.

4. Means for drying and shaping hosiery comprising, in combination, a drying form 60 having a groove formed in each of its edges, a pair of arms pivotally mounted adjacent said form, blades pivotally mounted on said arms, and means to rock said arms whereby said blades will be moved into and out of 65 said grooves.

5. Means for drying and shaping hosiery comprising, in combination, a drying form having a groove formed in each of its edges, 70 a collar clamped on said form adjacent its base, a pair of arms pivotally mounted on said collar, a blade pivotally mounted on each of said arms adjacent one end thereof, links connected to said arms at their other ends, a rod pivotally connected to said links, 75 tension means acting to move said rod in one direction whereby said arms will be rocked in one direction to enter said blades in said grooves, and manually operated means for moving said rod in the opposite 80 direction whereby said arms will be rocked oppositely to move said blades out of said grooves.

6. Means for drying and shaping hosiery comprising, in combination, a drying form 85 having a groove formed in the surface thereof, and a blade mounted on said form for movement out of and into said groove in a direction approximately perpendicular to the direction of extent of the groove and 90 without substantial movement in the direction of the length of the groove, whereby fabric on the form may be folded into the groove without being drawn along the form in the direction of the groove. 95

In testimony of which invention, I have hereunto set my hand, at Philadelphia, Pennsylvania, on this 8th day of Sept., 1925.

FREDERICK J. KIENEL.
